UNITED STATES PATENT OFFICE

GERARD A. DE VLIEG, OF ROCKFORD, ILLINOIS

REAMER

Application filed October 9, 1925. Serial No. 61,389.

The invention relates to improvements in adjustable reamers, and has particular reference to reamers of the expansion type.

One of the objects of the invention resides in the provision of a novel reamer having an expandible blade unit, and a pilot sleeve with expanding means coacting with the front end of said unit for adjusting the latter.

Another object is to provide a new and improved reamer in which the greatest expansion will occur at the foremost cutting surfaces where the wear is the greatest and regrinding is most necessary.

Other objects of the invention are to provide a reamer of the above character which is simple and inexpensive in construction, which may be easily, quickly and accurately adjusted, and which is efficient and long lived in use.

Ancillary objects and advantages will become apparent from the following description taken in connection with the accompanying drawings, in which

Figure 1 is an elevational view of a reamer embodying the features of my invention.

Fig. 2 is a longitudinal sectional view taken along line 2-2 of Figure 1.

Fig. 3 is a transverse sectional view taken along line 3-3 of Figure 1.

Fig. 4 is a fragmentary view partially in section of the driving connection between the shank and the blade unit.

Fig. 5 is a sectional view of the expanding means.

Fig. 6 is a sectional view taken along line 6-6 of Fig. 2.

While the invention is susceptible of various modifications and alternative constructions, I have shown in the drawings and will

herein describe in detail the preferred embodiment, but it is to be understood that I do not thereby intend to limit the invention to the specific construction disclosed, but aim in the appended claim to cover all modifications and alternative constructions falling within the spirit and scope of the invention.

Referring to the drawings, the reamer comprises a shank 7 adapted to be mounted in a suitable holder (not shown) and having a long coaxial cylindrical extension 8. A

blade unit 9 which is tubular in form, i. e. in the form of a sleeve, is loosely and removably mounted on the extension 8. The back or left end of the blade unit 9 is provided with a collar 10 which is formed with an outwardly flaring taper 11 in its inner surface. The tapered portion seats on a conical shoulder 12 (see Fig. 4) on the shank 7 which backs up the unit 9 and serves to locate it concentrically of the axis of rotation. A plurality of spaced longitudinal keyways 13 are formed in the periphery of the shank 7 next to the shoulder 12 and coact with clutch projections 14 on the adjacent end of the collar 10 to provide a suitable driving connection for the blade unit 9.

The forward end of the blade unit 9 consists of a section 15 which is formed with a plurality of blades 16 separated by flutes 17, and which is split longitudinally by a plurality of slots 18. In the present instance, four slots 18 are provided and the blades 16 are straight. It is to be understood, however, that the blades and slots may be of any suitable form or number. The slots 18 extend from the collar 10 along certain of the flutes 17 to the forward edge of the section 15.

To adapt the reamer for reaming aligned holes it is constructed with a pilot as is common in the art, but it is to be understood that the pilot may be dispensed with if desired. The pilot comprises a tube 19 fitting snugly on the forward end of the extension 8. A pin 20 on the pilot tube 19 projects into a longitudinal keyway 21 in the extension 8 and serves to feather the tube to the extension. The tube 19 may be adjusted longitudinally by means of a nut 22 threaded onto the end of the extension 8.

The back or left end of the tube 19 is provided with an annular wedging member 23 which is threaded externally, and which terminates in a taper 24 engaging a taper 25 on the inner edge of the split end of the blade unit 9. A knurled nut 26 on the wedging member 23 is formed with an inward taper 27 fitting over a taper 28 on the outer edge of the unit 9, and serves to limit the outward movement of the blades.

To adjust the reamer the nut 22 is loos-

ened, and the nut 26 is moved into a new position on the wedging member 23. The nut 22 is then turned to move the taper 24 inwardly along the taper 25 thereby expanding the forward end of the blade unit 9 until the taper 28 engages the taper 27. The latter limits the expansion of the reamer, and upon tightening the nut 22 serves to lock the reamer in its adjusted position.

10 It will be evident that I have provided a reamer simple and inexpensive in construction which can be expanded at the forward end where the wear is greatest and the need for regrounding most frequent. Only the 15 blade unit 9 need be made of good steel, and carefully tempered. Furthermore, different kinds of blade units may be substituted, thereby requiring but one shank and one adjusting means for a large number of units, 20 and reducing the amount of equipment required.

I claim as my invention:

A reamer having, in combination, a shank having an axial extension, an expansible 25 blade unit mounted on said extension, said unit being slotted from its forward end along its blades and being tapered at the inner and outer edges of the front end, a pilot tube splined to the front end of said extension and 30 having an expansion wedge engaging the taper on the inner front edge of said unit, means on said extension for moving said pilot member longitudinally, and a locking member threaded onto said pilot member 35 and having a taper engaging the taper on the outer front edge of said unit.

In testimony whereof, I have hereunto affixed my signature.

GERARD A. DE VLIEG.
